UNITED STATES PATENT OFFICE

JAMES POWERS, OF WASHINGTON, DISTRICT OF COLUMBIA.

COMBINED PUNCHING AND COUNTING MECHANISM.

992,245.

Specification of Letters Patent. Patented May 16, 1911.

Application filed April 8, 1908, Serial No. 425,831. Renewed October 15, 1910. Serial No. 587,311.

To all whom it may concern:

Be it known that I, JAMES POWERS, a citizen of the United States, residing in the city of Washington, in the District of Columbia, have invented certain new and useful Improvements in Combined Punching and Counting Mechanism, of which the following is a specification:

This invention relates to perforating or punching machines, the present embodiment relating more particularly, however, to that class of machines designed for punching census and other like forms of cards, the object of the present improvement being to provide a combined perforating and counting machine in which the cards may not only be perforated, but certain of such perforated items registered, so that when all of the cards of a certain series have been perforated the total of the items can be immediately ascertained, thus doing away with a separate perforating and counting mechanism, which was heretofore necessary.

A further object of the invention is the provision of an improved machine in which all the perforations on the card may be made at one time, and in which furthermore, the operator may determine, prior to the making of such perforations, whether or not the card will be properly punched to accord with the facts to be indicated.

A further object of the invention is the provision of an improved machine of the class specified, in which, when the card is perforated to accord with the items to be indicated, the card will also be marked or perforated prior to its removal from the machine by an independent means, whereby the card may always be properly classified instead of, as heretofore, requiring this to be done by a separate and independent punching apparatus.

In the drawings accompanying and forming part of this specification, Figure 1 is a front view of this improved machine; Fig. 2 is a side view thereof, with a part of the frame-work broken away to more clearly illustrate the mechanism, said view illustrating in dotted lines one of the keys depressed; Fig. 3 is a top or plan view of this improved machine, parts thereof being broken away more clearly to illustrate the mechanism; Fig. 4 is a cross sectional view, parts in elevation, taken in line *a*—*a*, Fig. 5, looking in the direction of the arrow; and Fig. 5 is a detail cross sectional view of

a part of the key mechanism and the counting mechanism, illustrating how the counting mechanism is operated on the shifting of the keys.

Similar characters of reference indicate corresponding parts throughout the different figures of the drawings.

The present improvement comprises in a general way a punch selecting means, or what may be properly designated as key mechanism for determining the particular punch or punches to be used and for locking that punch or punches in position to properly perform the required work; means operative, after the punches have been properly selected and locked in position to do the required work, for insuring the perforation of the card by all of the selected punches at one time; means connected with part of the mechanism and shown herein as connected with the keys, for registering or counting up certain of the items punched; means, usually designated a gang punching mechanism, for punching certain items on the card so that all cards of a certain series will be punched alike, whereby the cards may be readily classified; means for automatically releasing all of the punch selecting keys thereby to permit them to return to their normal position; all of which means or mechanisms are, in the present embodiment of the machine and after the keys have been individually selected and operated in accordance with the items to be punched, thrown into operation on the shifting of a single lever or key, by the operator; and card carrying means combined with means for locking such carrier in its proper position to permit the card to be properly punched. Thus it will be observed that the present improvement comprises generally a mechanism in which the items to be punched may be successively selected before any one item is punched, and then all of such items punched in the card on the operation of a single lever, and in which certain items so punched may also, simultaneously with the punching thereof, be counted or registered.

In the present embodiment of this improved machine it is shown particularly adapted for use with that form of cards usually used in connection with the census, although it is to be understood that the machine, in the present or a somewhat modified embodiment, may be used for various purposes.

In the preferred form shown suitable frame-work is provided for the support of the several mechanisms hereinafter described. This frame-work, in the present instance, 5 comprises a base 1 supporting what may be designated as a basket frame 2, this latter comprising a lower supporting portion consisting of a pair of inwardly extending brackets 3 and 4 for carrying the punch sup- 10 porting plate 5 and the plate 6 which guides the lower ends of the key levers hereinafter described, and a top or platform 7 having openings 8, shown herein as circular, there- 15 through one for each of the key levers 9. Secured to the base is a pair of brackets 10 having sleeves 11 for the reception of the driving shaft 12. Mounted loosely on this driving shaft is a driving pulley 13, which is continuously rotated from any suitable 20 source of power.

Supported below the punch carrying plate 5, and in the base of the frame-work, is a die carrying support comprising a suitable frame 14 having a pair of flanges 15, one at 25 each end, sliding in ways 16 located interiorly of the end of the base of the frame. For shifting this die plate 14 suitable means is provided, shown comprising a pair of L-shaped levers 17 pivoted to the ends of the 30 die plate frame 14 by means of studs 18 passing through the ends of the base and which are provided with elongated slots 19 to permit the proper rise and fall of the die carrying frame. These L-shaped levers 35 are pivoted to the base, as at 20, exteriorly thereof and their upper ends are connected, through the medium of a pair of adjustable links, with eccentric straps 22 mounted on a pair of eccentrics 23 rigidly secured to the 40 driving shaft. These links, as stated, are adjustable whereby the throw or sliding movement of the die carrying frame may be regulated.

A suitable connection is provided between 45 the loosely mounted pulley and one of the fixedly mounted eccentrics, whereby at a predetermined period the constantly rotating pulley will shift the eccentric and so shift the die carrying frame. In the present 50 instance this consists of a shiftable pin 24 carried by that eccentric which is adjacent to the loosely mounted constantly rotating pulley. This pin is shown extending 55 through the eccentric, being carried there- by for rotary movement therewith, and is spring actuated to throw the pin outwardly into position to be engaged by a projection or lug 25 carried on the inner face of the loosely mounted driving wheel. This con- 60 nection between the driving wheel and the eccentric is controlled by a lever or key 26 pivoted to the side of the base and main- 65 tained in its normal position by means of a spring 27 connected to one end thereof and to the base. Connected with a projecting

part, as 28, of this lever is a link 29, the opposite end of which is pivoted to a pin actuating device 30 in the form of a lever pivoted on the base of the frame, this lever being outwardly bent or inclined whereby it 70 forms a pin-engaging cam, it being in such position that it will engage the head 31 of the spring-actuated pin or stud 24 carried by the eccentric and shift the same against the action of its spring and out of connec- 75 tion with the driving wheel. On manually shifting this key or lever 26 the pin engag- 80 ing lever will be shifted away from the head 31 of the pin 24 so that its spring will force the pin into position to be engaged by the projection or lug 25 on the driving wheel. In operation, the rotation of the driving wheel will carry, through the medium of this connecting pin, the eccentric around one revolution, thereby to raise and lower the 85 die carrying frame; the head 31 of the pin 24, as the eccentric completes its revolution, being brought into position to be engaged by the lower inclined portion of the cam lever 30 of the operating key 26, which, owing to 90 its outwardly bent formation or inclined position, will shift the pin on the further rotation of the eccentric to withdraw it from the projection 25 of the driving wheel.

The punching mechanism in the present 95 instance comprises a series of punches ar- 100 ranged in two sets, one set comprising a se- ries of punches 32 corresponding in number with the number of actuating keys or punch selecting devices 9, the other set 33 comprising the desired number for classifying the 105 cards and which are not under the control of the keys. Co-operating with these two sets of punches is a die member 34 having a series of openings 35 therethrough, corre- 110 sponding in number with the number of punches of both sets, this member being carried on the sliding die carrying frame 14 hereinbefore described for movement there- 115 with and into position to permit the punches to pass into the openings in such member. These punches and the die member consti- 120 tute the male and female dies forming the card perforating means for punching the required perforations in the card, which is carried by the die member in the manner hereinafter described.

The punches are shown formed as headed pins having suitably formed punching ends and carried by the punch supporting plate 125 5, through the openings of which the punches extend, the heads resting upon such plate. This plate 5, with its punches, may be slid into and out of position as it is sup- 130 ported by grooves 36 formed in the brackets 3 and 4 of the basket frame. Above this plate 5 is fixedly secured the key guiding plate 6, which is likewise secured to the brackets 3 and 4. This plate 6 is provided with open- 135 ings therethrough, corresponding in number

with the key levers 9, one for the end of each lever, the openings in the plate being so located as to bring the ends 37 of the key levers 9 just above the heads of the punches. 5 In the present embodiment the key levers 9 are shown as converging inwardly, so that the ends will pass into said openings. Each of these key levers is provided with a suitable finger-piece 38 carrying the designating 10 character thereon, and which, of course, can be readily changed by the removal of this finger piece or cap. Each of the key levers, corresponding in number, as hereinbefore stated, with the number of the punches 32 15 that make up one set thereof, is shown provided with an offset 39 and is maintained in its normal position by means of a suitable spring 40. Various forms of springs may be used to maintain the lever in its proper 20 position, as for instance spiral springs located around the shanks of the levers underneath the caps, but these springs are shown connected one end of each to the underside of the top or platform 7 of the frame-work 25 and the other end with one of the key levers, the springs being so located that when each key is depressed, as shown by the dotted lines in Figs. 2 and 5, the key will be pulled or shifted into such position that the offset 30 39 of the key will come under the underside of the platform or top 7 and thus the key be held down in its punch locking position. In other words, as each key is depressed against the tension of its spring this spring will act 35 to shift the key so that the offset thereon will lock the key in its depressed position with the lower end 37 thereof in juxtaposition to its particular punch, whereby the upward movement of such punch is prevented. 40 When the desired number of keys have been thus manipulated and the punches of the set 32 locked against upward movement, it will be seen that as the die plate is shifted upward with the card to be punched those 45 punches which are locked in position will perforate the card, while the other punches which are not thus locked in position will be shifted upward in the punch carrying plate 35 by the card itself, the weight of such 50 punches not being sufficient to perforate the card. After the desired keys have been manipulated to thus select the punches which are to perforate the card and lock them in position the operator may then, by an examination of the depressed keys, immediately determine whether she has depressed the proper keys. This being determined the operator will then operate the key 26, whereupon connection will be made between the 55 eccentric and the constantly rotating driving wheel to thereby shift the die carrying plate and its card upwardly into engagement with the key locked punches, whereupon the card will be perforated in a manner 60 that will be readily understood, by those

punches only which are locked against movement by the keys. After the card is properly punched in the manner just described, the die carrying plate, together with the card is lowered away from the punches 70 and the keys all released and returned by the action of the springs to their normal positions, while the punches remain hanging in the plate 5. This releasing of the keys is obtained in the present embodiment by means 75 of suitable key releasing means comprising, in the present instance, a shiftable or sliding plate 41 carried on the top of the platform or top 7 of the basket frame and provided with rectangular or elongated slots 42, one 80 for each key lever. Suitable ways, formed by means of L-shaped brackets 43 secured to the ends of the top 7, are provided for guiding the plate. The plate is connected to a rock shaft 44 by a pair of rock arms 45, 85 the shaft being supported by brackets 46 carried by the frame-work at the rear thereof, and fixedly secured to this shaft is an arm 47 pivotally connected to a lever or link 48 the lower end of which in turn is connected to a link 49 fixed at its inner end to a sliding pin 50 carried by suitable brackets in which the pin 50 works. These brackets 51 are carried by a bar 51' fixedly secured at and extending crosswise of the rear of 90 the frame-work. A spring 52 is carried on the sliding pin between the link 49 and the upper bracket 51 and holds the lower end of this pin in contact with a cam 53 secured to the driving shaft 12, whereby, as this shaft 100 is rotated through the medium of the eccentrics hereinbefore described, the cam will raise and lower the pin 50 and thereby the link 48 and rock the shaft 44 and thereby shift the key releasing plate 41, the movement of which, as will be readily understood by an examination of Fig. 5, will shift the keys so that their offsets will be withdrawn from under the top or platform 7. In other words, after the punching of the card the 105 cam face 53 will be brought into engagement to raise the pin 50, which will, as stated, rock the shaft 44 and thereby the arms 45 and so throw the plate toward the rear or right hand as shown in Fig. 2, whereupon the plate will engage all of the levers which are in depressed position and move them so as to withdraw them from under the top or platform 7 and permit them to return by means of their springs to their normal position. Cross pins 40' engage the underside of a shiftable plate 41 and limit the upward movement of the keys. 110 In a machine of this character it is necessary that all the cards of a series shall be punched in one or more places alike, that is to say, if the population and its characteristics for a particular locality is being recorded, then all of the cards for that locality should be classified in such a manner that 115 120 125 130

should any one or more of the cards get out of place it can be readily determined to what locality it belongs; that is to say, if a certain perforation indicates the city of Washington, then all of the cards which are used to record the population and the characteristics of the inhabitants of Washington should all be perforated alike at the same point, so that should one of the cards 10 be accidentally misplaced or lost it can be immediately determined to just what package or bundle it should be returned. Heretofore, however, this has been done subsequent to the main punching of the cards, 15 by means of an independent punching apparatus, a series of cards being usually punched at the same time. Consequently, should the operator drop a card on the floor or otherwise misplace the same prior to 20 its being punched to indicate to what class it belongs there has been no means of ascertaining to what locality the card belongs and to what class or series of cards it should be returned. To do away with the above 25 mentioned serious disadvantage I have provided means in the present improvement whereby, simultaneously with the punching of the various data by the punches 32 of the main set of punches, the card will also 30 be punched to indicate the class to which it belongs. This is accomplished in the present instance by that part of the die mechanism in which the punches 33 form a part and which are not under the control of the 35 keys, as hereinbefore stated. These punches 33, formed like the punches 32, are in position with the heads thereof in juxtaposition to an overhanging part 60 of the bracket 4. Only certain of these punches, however, 40 are placed in position. For instance, if a certain punch indicates the city of Washington and the cards being worked upon are for that locality, then that punch only of this gang of punches 33 will be inserted in 45 the punch carrying plate 5; the remaining punches of the gang being removed, this being permitted by withdrawing the punch carrying plate 5 on the brackets 3 and 4 in the manner hereinbefore described and setting the particular punches of the gang 33 which it is desired shall punch each successive card of the series in the same place. When the plate 5 is returned with the desired punch or punches of the set 33 in position, it will be seen that the overhanging part 60 of the bracket 4 will lock such punch or punches against upward movement in precisely the same manner as the key levers 9 lock, when such levers are depressed, the 55 punches 32 in perforating, so that when the die plate and its card is carried upwardly those punches 33 which are carried by the plate will punch perforations through the 60 card.

The die or die member 34 hereinbefore referred to comprises a pair of plates 61 and 62 having registering openings there-through, corresponding in number with the number of punches in the machine. These plates are fixedly connected for rigid attachment to the shiftable die carrying frame, but are spaced apart, as at 65, for the reception between them of the card and its carrier.

The card supporting means in the present 75 instance comprises a forwardly extending shelf 63 secured to the front of the die member, it being provided in its bottom with a pair of openings 64 to permit the operator to insert her fingers to engage the 80 card underneath thereof after the same has been perforated and quickly push or remove the same from its frame, and a card carrying frame 66 shiftable on said shelf into position between the die plates 61 and 62. 85 This frame is spring controlled in the present instance. The forward end of the frame, which is provided with a thumb-piece 72, is connected by means of a cord 67 running over a pulley 73 carried on the underside of the shelf, with a spring tensioned drum 68, likewise supported on the underside of the shelf, whereby the frame is maintained in its forward position. When the card is laid on the frame and the same 90 is pushed inwardly by means of the thumb-piece to carry the card between the plates 61 and 62, suitable means is provided for locking the frame in such position thereby to always properly position the successive 95 cards. This locking means comprises in the present instance a pair of pins 69 guided in the side walls 74 of the shelf, the opposite and longer ends 75 of the pins being connected to a lever 70 pivoted intermediate 100 its ends to the underside of the shelf, the end of one of said locking pins being connected with a spring 76 also secured to the underside of the shelf. Connected to one 105 of the levers is an actuating lever 71, likewise pivoted to the underside of the shelf and extending forwardly into position to be actuated by the operator. When the card carrying frame is pushed inward by its thumb-piece to properly position the card 110 between the die plates 61 and 62, the spring 76 of the locking pins forces the locking ends of the pins into position behind the front wall of the card carrier, thereby automatically locking such carrier with its 115 card in position to permit the proper perforation of the card. After the card has been perforated the manipulation of the lever 71 shifts the pins outwardly, thereby unlocking the card carrier and permitting the spring 120 actuated drum to draw the same to the front of the shelf, whereupon the card can be removed. The sides of the card carrier or 125

frame, during the sliding of the card into position, hold the ends of the locking pins out of their locking position until the front of such frame has passed the pins, whereupon, as hereinbefore stated, these pins, through the medium of their springs, are forced back of the front wall of such card carrier, thereby locking it in the manner just described.

10 From the foregoing, it will be seen that when the card is placed in position on the card carrier and the latter pushed inwardly through the medium of its thumb-piece, the card will be carried into position between the die plates 61 and 62 to be perforated, whereupon, on the shifting of the key 26 the die, together with the card carrying frame, will be shifted upward by the die frame and the card properly perforated and with- 15 drawn from the punches, the plate 62 preventing the card from remaining on the punches as the die and its frame return to its normal position. After the card is prop- 20 erly perforated the manipulation of the lever 25 71 unlocks the card carrier, whereupon the same is carried forward automatically into position to be removed in the manner herein- before described.

Heretofore it has not been practicable, 30 after the cards have been perforated, to ascertain certain data until the same has been separately compiled, so that it has not been possible to ascertain certain statistics even after the entire series of cards have been 35 perforated without this separate compilation. For instance, it has not been possible to ascertain the number of inhabitants of a certain city, even after all the cards indicating the number of inhabitants and the 40 characteristics thereof have been perforated, until this data has been separately compiled, sometimes requiring many months of time. In order to do away with this disadvantage and register or count up this data as each 45 successive card is perforated, I have provided an improved means for counting this data as the successive cards are perforated, so that when all the cards of a series have been completely perforated it can be deter- 50 mined at a glance just the number of inhab- itants in that locality, or in the country, and also the number of white inhabitants, the number of males or the number of females, which it may be desired to immediately ascer- 55 tain when the series of cards have been completely perforated, and this without any sepa- rate compilation. In the present embodiment I provide a registering or counting mechanism for each particular item or fact, 60 as for instance, the number of males or the number of females, or the number of inhab- itants in a certain locality which it is de- sired to ascertain as the cards are per- 65 forated. It will, of course, be understood that

as many of these registering mechanisms 65 may be provided as there are facts or items to be compiled, but in practice it is usually only desirable to ascertain in this manner the main items, as for instance the number of inhabitants or the number of males or 70 females, the race, etc., of a certain locality. This improved counting mechanism com- 75 prises, in the present instance, some suitable form of counting or registering device, such as a counter, one for each key, according to 80 the number of keys it is desired to have the counting mechanism attached to. In the present instance the frame-work is shown provided with a back plate or upright 80 having openings 81. Attached to the front 80 of this upright, and adjacent to each opening is located a counter 82, nine of them being shown in the present drawings attached to nine keys, one to each. In the present improvement the registering mechanism is 85 controlled by the keys, and for this purpose each key is connected with its counter by a lever system. Each of these systems com- 90 prises a sliding bar 83 suitably guided in the frame-work and connected by a link 84 with 95 its key. The rear end of this bar 83 is piv- 100 otally connected by a link 85 with a connect- ing lever 86 the upper end of which extends through one of the openings in the upright and is connected with the counter. The link 95 105 85 is provided with a recess 87 in its upper edge, which is normally in position under a cross-bar 88 connected adjacent its opposite ends with a pair of shiftable posts 89, each pivots connected by a pair of parallel 100 links 90, 91 with a post 92, which posts are secured to the upper part of a frame 92' se- 110 cured to the rear of the die carrier and suit- ably guided in a pair of brackets 93' extend- 115 ing out from the cross-bar 51'. The lower 105 link 91 of each pair of parallel links is piv- 120 otally connected to a bracket 98, so that these links 90 and 91 thus act as an equalizer.

From the foregoing it will be observed that when one of the keys is depressed, see 110 Figs. 2 and 5, it will shift the bar 83 for- 115 ward, thereby drawing the link 85 into such position that the recess 87 therein will be shifted away from underneath the bar 88, so that when said bar 88 is drawn down- 120 ward it will engage the face 94 of the shifted link 85 and thus depress the connecting rod 86 and actuate the counter, such bar 88, however when drawn downward entering the recesses 87 of all those links which have 120 not been shifted by the keys, so that the counters attached to the undepressed keys will not be operated. The drawing of this bar 88 downward takes place as the die car- 125 rier frame moves upward, for as this frame is shifted upwardly it shifts the sliding frame 92' also upwardly, thus drawing down the posts 89, which, through the medium of

the parallel links 90 and 91, draw downward the bar 88, which, as just stated, will at this time engage the faces 94 of the link 85 and operate the counter. The return of 5 the die carrier frame returns these operating parts to their normal position. Thus, it will be observed that the depression of the key, even though this particular key be attached to a counter, will not in itself operate 10 such counter, the operation of such registering mechanism taking place only when the main key 26 of the mechanism is operated, in other words, only when the card is punched by all of the punches which have 15 been locked in their punching position.

From the foregoing it will be seen that if one of the counters is attached in the manner set forth to that key, for instance, which indicates the number of males in a certain 20 locality, it follows that each time this particular key is operated, once for instance for each card, and the card is perforated accordingly, the counter attached to this key will be operated, so that after a certain number, ten or fifteen thousand or more cards 25 have been perforated the counter will show at a glance that a sufficient number of cards have been perforated to indicate a population of ten or fifteen thousand male inhabitants. Thus, without any additional compilation or separate machines, certain data 30 can be immediately ascertained as soon as all the cards of a series have been perforated. The registering mechanism also indicates the 35 number of cards that have passed through the machine and it can be determined at a glance, for instance, what the male population is as each successive card passes through the machine.

40 In the old way of perforating cards, should one of the perforations be misplaced the entire card must be thrown away, even though all the other perforations therein were correctly placed. By means of the 45 present improvement, however, as the card is not perforated until after all of the punches have been properly set, the operator thus has an opportunity of observing before the perforation of the card takes place 50 whether all the punches are properly set and should one or more be improperly set she has an opportunity of correcting this before a card is wasted. Thus considerable time is saved as well as loss of cards prevented by 55 this improved machine. Moreover, by the present improvement, a number of punches can be operated at the same time, corresponding with the fingers of the hands of the operator. The machines now most generally used in connection with the census 60 permit only one perforation to be made at a time; but by the present improvement the operator may depress a number of keys at one time, according to her ability to manipulate her fingers and thumbs, thus turning out 65

work very much faster than has been the usual practice.

I claim as my invention:

1. In a machine of the class specified, the combination of punching mechanism, key operated selecting and locking mechanism for parts of said punching mechanism, and power driven means for shifting the unlocked coöperating part only of said punching mechanism subsequent to the locking of 75 the parts.

2. In a machine of the class specified, the combination of punching mechanism, key operated selecting and locking mechanism for parts of said punching mechanism, and power driven means for shifting the unlocked coöperating part only of said punching mechanism subsequent to the locking of 80 the parts and controlled by a single lever.

3. In a machine of the class specified, the combination of punching mechanism, key operated selecting and locking mechanism for parts of said punching mechanism, power driven means for shifting the unlocked coöperating part only of said punching mechanism subsequent to the locking of 85 the parts, counting mechanism, and means for operating it simultaneously with the shifting of said unlocked parts of the punching mechanism.

4. In a machine of the class specified, the combination of punching mechanism, key operated selecting and locking mechanism for parts of said punching mechanism, power driven means for shifting the unlocked coöperating part only of said punching mechanism subsequent to the locking of 90 the parts, counting mechanism, and means for operating it simultaneously with the shifting of said unlocked parts of the punching mechanism.

5. In a machine of the class specified, the combination of punching mechanism comprising a movable die and a series of punches, means effective to select and lock one of said parts in position, and power driven means effective to shift the unlocked part of the punching mechanism into position to coöperate with the other.

6. In a machine of the class specified, the combination of punching mechanism including a series of punches and a movable die, keys effective to select and lock the individual punches in position, and means effective to shift the die into position to coöperate with the punches.

7. In a machine of the class specified, the combination of punching mechanism including a series of punches and a die, keys effective to select and lock the individual punches in position, means effective to shift the die into position to coöperate with the punches, and means effective to throw said die shifting means into operation subsequent to the 125 130

locking of a predetermined number of punches.

8. In a machine of the class specified, the combination of punching mechanism including a series of punches and a die, keys effective to select and lock the individual punches in position, means effective to shift the die into position to coöperate with the punches, and a key effective to throw said die shifting means into operation subsequent to the locking of a predetermined number of punches.

9. In a machine of the class specified, the combination of punching mechanism including two sets of punches and a die coöperating with both sets thereof, keys effective to select and lock the individual punches of one set in position, and means effective to shift the die into position to coöperate with both sets of punches.

10. In a machine of the class specified, the combination of punching mechanism including two sets of punches and a die coöperating with both sets thereof, keys effective to select and lock the individual punches of one set in position, and key controlled means effective to shift the die into position to coöperate with both sets of punches.

11. In a machine of the class specified, the combination of punching mechanism including two sets of punches and a die coöperating with both sets thereof, keys effective to select and lock the individual punches of one set in position, and a single key controlled means effective to shift the die into position to coöperate with both sets of punches.

12. In a machine of the class specified, the combination of punching mechanism including two sets of punches and a shiftable die, the punches of one set all permanently locked in position, keys effective to select and lock individual punches of the other set against movement, the unlocked punches of said last set being free for movement, and key controlled means for shifting the die into position to coöperate with both sets of locked punches.

13. In a machine of the class specified, the combination of punching mechanism including two sets of punches and a shiftable die, the punches of one set all permanently locked in position, keys effective to select and lock individual punches of the other set against movement, the unlocked punches of said last set being free for movement, key controlled means for shifting the die into position to coöperate with both sets of locked punches, and card carrying mechanism for positioning a card to be perforated.

14. In a machine of the class specified, the combination of punching mechanism including two sets of punches and a shiftable die, the punches of one set all permanently locked in position, keys effective to select

and lock individual punches of the other set against movement, the unlocked punches of said last set being free for movement, key controlled means for shifting the die into position to coöperate with both sets of locked punches, card carrying mechanism for positioning a card to be perforated, and means for automatically locking said card carrying means in its perforating position.

15. In a machine of the class specified, the combination of punching mechanism including two sets of punches and a shiftable die, the punches of one set all permanently locked in position, keys effective to select and lock individual punches of the other set against movement, the unlocked punches of said last set being free for movement, key controlled means for shifting the die into position to coöperate with both sets of locked punches, card carrying mechanism for positioning a card to be perforated, means for automatically locking said card carrying means in its perforating position, and means for releasing said card carrying means.

16. In a machine of the class specified, the combination of punching mechanism including two sets of punches and a shiftable die, the punches of one set all permanently locked in position, keys effective to select and lock individual punches of the other set against movement, the unlocked punches of said last set being free for movement, key controlled means for shifting the die into position to coöperate with both sets of locked punches, card carrying mechanism for positioning a card to be perforated, means for automatically locking said card carrying means in its perforating position, and lever actuated means for releasing said card carrying means thereby to permit the same to be automatically shifted away from the die.

17. In a machine of the class specified, the combination of punching mechanism including two sets of punches and a die, one set permanently locked in position, keys effective to select and lock the individual punches of the other set in position, and means for shifting said die and comprising mechanism including a constantly rotatable pulley, an eccentric mechanism, one of said parts carrying a spring controlled pin and the other a stop, a key for releasing said pin thereby to form connection between said eccentric mechanism and driving pulley, and means for shifting said pin thereby to disconnect said parts after each complete shifting of the die.

18. In a machine of the class specified, the combination of punching mechanism including a series of punches and a die, means for selecting the punches to be used, means for shifting said die and comprising a constantly rotatable driving pulley, an eccentric, connecting means between said eccentric and the die, said pulley and eccentric

carrying one a stop and the other a shiftable pin, and key operated means for releasing said pin thereby to connect the eccentric with said pulley and shift the die, and 5 means for releasing said pin from the stop on each complete shifting of the die.

19. In a machine of the class specified, the combination of punching mechanism including a series of punches and a die, means 10 for selecting the punches to be used, means for shifting said die and comprising a constantly rotatable driving pulley, an eccentric, connecting means between said eccentric and the die, said pulley and eccentric 15 carrying one a stop and the other a shiftable pin, key operated means for releasing said pin thereby to connect the eccentric with said pulley and shift the die, and means comprising a cam formed member for releasing said pin from the stop.

20. In a machine of the class specified, the combination of punching mechanism including a series of punches and a die, keys effective to select the particular punches to be 25 used, means for locking the keys in their depressed position, means for shifting the die, and means for automatically releasing the keys as the die returns to its normal position.

30 21. In a machine of the class specified, the combination of punching mechanism including a series of punches and a die, keys effective to select the particular punches to be used, means for locking the keys in their 35 depressed position, means for shifting the die, and means for automatically releasing the keys as the die returns to its normal position, said means comprising a shiftable plate having a part in engagement with each 40 of said keys.

22. In a machine of the class specified, the combination of punching mechanism comprising a series of punches and a die, means for shifting said die, spring controlled keys 45 operative to select the particular punches to be used, means for locking each of the depressed keys, and means actuated by the die shifting means for releasing all the locked keys simultaneously.

50 23. In a machine of the class specified, the combination of punching mechanism comprising a series of punches and a die, keys operative to select the particular punches to be used, means for locking each of the manipulated keys against movement, means controlled by a single actuating key for shifting said die, and means actuated by 55 said die shifting means for unlocking all of said keys.

60 24. In a machine of the class specified, the combination of punching mechanism comprising a series of punches and a die, keys operative to select the particular punches to be used, means for locking each of the manipulated keys against movement, means

controlled by a single actuating key for shifting said die, and means actuated by said die shifting means for unlocking all of said keys simultaneously and comprising a sliding member in operative connection with 70 the keys.

25. In a machine of the class specified, the combination of punching mechanism comprising a series of punches and a die, keys operative to select the particular punches 75 to be used, means for locking each of the manipulated keys against movement, means controlled by a single actuating key for shifting said die, and means actuated by said die shifting means for unlocking all of said keys simultaneously and comprising a sliding plate operatively connected with 80 each of the keys.

26. In a machine of the class specified, the combination of punching mechanism comprising a series of punches and a die, keys for selecting the particular punches to be used, each of said keys having an offset, means operative to shift the keys on the depression thereof into position to permit 90 said offsets to lock the keys, means for releasing all of said keys simultaneously, and means for shifting said die.

27. In a machine of the class specified, the combination of punching mechanism comprising a series of punches and a die, keys for selecting the particular punches to be used, each of said keys having an offset, 95 means operative to shift the keys on the depression thereof into position to permit said offsets to lock the keys, means for releasing all of said keys simultaneously, and means for automatically releasing said keys and including a sliding plate having openings through each one of which a key projects. 100 105

28. In a machine of the class specified, the combination of punching mechanism comprising a series of punches and a die, keys for selecting the particular punches to be used, each of said keys having an offset, 110 means operative to shift the keys on the depression thereof into position to permit said offsets to lock the keys, means for releasing all of said keys simultaneously, means for automatically releasing said keys and including a sliding plate having openings through each one of which a key projects, 115 120

29. In a machine of the class specified, the combination of punching mechanism comprising a series of punches and a die, keys for selecting the particular punches to be used, each of said keys having an offset, means operative to shift the keys on the depression thereof into position to permit said offsets to lock the keys, means for releasing all of said keys simultaneously, means for automatically releasing said keys and in- 125 130

- cluding a sliding plate having openings through each one of which a key projects, means for shifting said die, means controlled by said die shifting means for shifting said key releasing plate, and a key for controlling said die shifting means and said key releasing means.
30. In a machine of the class specified, the combination of punching mechanism including a series of punches and a movable plate co-operating therewith, keys for selecting the particular punches to be used, means effective to lock the keys in their punch selecting positions, and means for shifting said plate into engagement with said punches after the locking of the keys, and means for automatically releasing said keys simultaneously after the punches have performed their work.
31. In a machine of the class specified, the combination of punching mechanism including a series of punches, keys for selecting the particular punches to be used, means effective to lock the keys in their punch selecting positions, and means for automatically releasing said keys simultaneously after the punches have performed their work, said releasing means comprising a sliding member having connection with each of said keys, a rotary cam, and lever mechanism intermediate said cam and sliding member for shifting said member.
32. In a machine of the class specified, the combination with a frame-work having a top plate provided with openings therein, of a series of key levers projecting through said openings, a sliding plate on said top plate and also having openings through which each of said key levers projects, each of said key levers having an offset, and means for shifting the key into position to permit the offset to engage the underside of the top plate on the depression of the key, and means for sliding said shiftable plate thereby to shift all of the depressed key levers to release them from the top plate.
33. In a machine of the class specified, the combination with a frame-work having a top plate provided with openings therein, of a series of key levers projecting through said openings, a sliding plate on said top plate and also having openings through which each of said key levers projects, each of said key levers having an offset and means for shifting the key into position to permit the offset to engage the underside of the top plate on the depression of the key, means for sliding said shiftable plate thereby to shift all of the depressed key levers to release them from the top plate, punching mechanism comprising a series of punches and a die, and means for shifting said die and also effective to operate the key releasing means.
34. In a machine of the class specified, the combination of punching mechanism in- cluding a series of punches and a die, keys effective to select and lock the individual punches in position, means effective to shift the die into position to co-operate with the punches, and counting mechanism operated simultaneously with the punching mechanism.
35. In a card punching machine, the combination of card punching mechanism, means for counting the data punched on successive cards thereby to indicate the total thereof, and power driven means for operating both the punching mechanism and counting means.
36. In a card punching machine, the combination of card punching mechanism, counting mechanism for counting the individual holes punched in the cards, and power driven means for actuating both the punching mechanism and counting mechanism in proper sequence.
37. In a card punching machine, the combination of card punching mechanism, key operated means for controlling the punching mechanism, counting mechanism for counting the individual holes punched in the cards, and power driven means for actuating both the punching and counting mechanisms in proper sequence.
38. In a card punching machine, the combination of card punching mechanism, key operated means for controlling the punching mechanism, counting mechanism for counting the individual holes punched in the cards, power driven means for actuating both the punching and counting mechanisms in proper sequence, and means for carrying a card into position to be punched.
39. In a card punching machine, the combination of card punching mechanism, counting mechanism for counting the individual holes punched in the cards, key operated means for controlling the operation of both of said mechanisms, power driven means for actuating both the punching and counting mechanisms, and a key operated lever for controlling the operation of said power driven means.
40. In a card punching machine, the combination of card punching mechanism, counting mechanism for counting the individual holes punched in the cards, key operated means for controlling the operation of both of said mechanisms, power driven means for actuating both the punching and counting mechanisms, a key operated lever for controlling the operation of said power driven means, and card carrying means effective to carry a card into position to be operated on by the punching mechanism.
41. In a card punching machine, the combination of card punching mechanism, counting mechanism for counting the individual holes punched in the cards, key operated mechanism for controlling the opera-

tion of said punching mechanism, power driven means for operating said punching and counting mechanisms, a key operated lever for controlling the operation of said power driven means, and automatically operative key releasing means.

42. In a card punching machine, the combination of card punching mechanism, counting mechanism for counting the individual holes punched in the cards, key operated mechanism for controlling the operation of said punching mechanism, power driven means for operating said punching and counting mechanisms, and automatically operative key releasing means, the power driven means being effective to operate said punching mechanism, counting mechanism and key releasing means in proper sequence.
43. In a card punching machine, the combination of card punching mechanism comprising a series of punches and a die, key operated levers effective to select and lock the individual punches in position, counting mechanism comprising one or more counters connected with one or more keys and effective for counting the holes punched by its key, and power driven means for shifting the die and operating the counters subsequent to the depression of the keys.

44. In a card punching machine, the combination of card punching mechanism comprising a series of punches and a die, key operated levers effective to select and lock the individual punches in position, counting mechanism comprising one or more counters connected with one or more keys and effective for counting the holes punched by its key, power driven means for shifting the die and operating the counters subsequent to the depression of the keys, and means for automatically releasing said keys after each card is punched.

45. In a machine of the class specified, the combination of punching mechanism comprising a series of loosely mounted punches, a movable die, power driven means for shifting said die into position to coöperate with said punches, key mechanism effective to select and lock the individual punches in position, means for locking the keys in their depressed positions, means for releasing all of the keys simultaneously, counting mechanism connected with certain of said keys, and a single operating key for throwing said die shifting means into operation thereby to shift the die and operate the counting mechanism.

46. In a machine of the class specified, the combination of punching mechanism comprising a series of loosely mounted punches, a movable die, power driven means for shifting said die into position to coöperate with said punches, key mechanism effective to select and lock the individual punches in

position, means for locking the keys in their depressed positions, means for releasing all of the keys simultaneously, counting mechanism connected with certain of said keys, a single operating key for throwing said die shifting means into operation thereby to shift the die and operate the counting mechanism, card carrying means, and means for locking said card carrying means in position to permit the card to be perforated.

47. In a machine of the class specified, the combination of punching mechanism comprising punches and a die consisting of a pair of apertured plates spaced apart for the reception of the work to be punched, the punches being carried by one of said plates, means for shifting said die, and means for carrying a card in a position between said apertured plates.

48. In a machine of the class specified, the combination of punching mechanism comprising punches and a die consisting of a pair of apertured plates spaced apart for the reception of the work to be punched, power driven means for shifting said die, and key operated means for selecting the punches.

49. In a machine of the class specified, the combination of punching mechanism comprising punches and a die consisting of a pair of apertured plates spaced apart for the reception of the work to be punched, means for shifting said die, key operated means for selecting the punches, and a work carrier shiftable intermediate said plates.

50. In a machine of the class specified, the combination of punching mechanism comprising punches and a die consisting of a pair of apertured plates spaced apart for the reception of the work to be punched, means for shifting said die, key operated means for selecting the punches, a work carrier shiftable intermediate said plates, and means for automatically locking said carrier in position between said plates.

51. In a machine of the class specified, the combination of punching mechanism comprising punches and a die consisting of a pair of apertured plates spaced apart for the reception of the work to be punched, means for shifting said die, key operated means for selecting the punches, a work carrier shiftable intermediate said plates, means for automatically locking said carrier in position between said plates, and means for releasing said locking means.

52. In a machine of the class specified, the combination of punching mechanism comprising punches and a die consisting of a pair of apertured plates spaced apart for the reception of the work to be punched, means for shifting said die, key operated means for selecting the punches, a work carrier shiftable intermediate said plates, means for automatically locking said carrier in position between said plates, means for releasing

said locking means, and means for automatically shifting the carrier away from the die on the unlocking of said carrier.

53. In a machine of the class specified, the combination of punching mechanism including a shiftable die and means for shifting said die, a work carrier shiftable with said die and transversely thereof, and means for locking said carrier in position adjacent to the die.

54. In a machine of the class specified, the combination of punching mechanism including a shiftable die comprising a pair of plates spaced apart, the dies being carried by one of said plates, means for shifting said die, a work carrier shiftable with said die and also shiftable intermediate said plates.

55. In a machine of the class specified, the combination of punching mechanism including a shiftable die comprising a pair of plates spaced apart, means for shifting said die, a work carrier shiftable with said die and also shiftable intermediate said plates, and means for locking said carrier in position between said plates.

56. In a machine of the class specified, the combination of punching mechanism comprising two sets of punches and a movable die, power driven means for shifting said die into position to coöperate with both sets of said punches, key levers effective to select and lock the individual punches of one set of punches in position, means for releasing all of said key levers simultaneously and operated by said power driven means, counting mechanism connected with certain of said key levers and preliminarily controlled by said key levers, means operated by the power driven means for actuating said counting mechanism, and a single operating key for throwing said power driven means into operation.

57. In a machine of the class specified, the combination of punching mechanism comprising two sets of punches and a movable die, the latter comprising a pair of plates spaced apart, power driven means for shifting said die into position to coöperate with both sets of said punches, key levers effective to select and lock the individual punches of one set of punches in position, means for releasing all of said key levers simultaneously and operated by said power driven means, counting mechanism connected with certain of said key levers and preliminarily controlled by said key levers, means operated by the power driven means for actuating said counting mechanism, a single operating key for throwing said power driven means into operation, and card carrying means secured to said die and shiftable therewith and also shiftable intermediate the plates of said die.

58. In a machine of the class specified, the combination of punching mechanism comprising two sets of punches and a movable

die, the latter comprising a pair of plates spaced apart, power driven means for shifting said die into position to coöperate with both sets of said punches, key levers effective to select and lock the individual punches of one set of punches in position, means for releasing all of said key levers simultaneously and operated by said power driven means, counting mechanism connected with certain of said key levers and preliminarily controlled by said key levers, means operated by the power driven means for actuating said counting mechanism, a single operating key for throwing said power driven means into operation, card carrying means secured to said die and shiftable therewith and also shiftable intermediate the plates of said die, and means for automatically locking said card carrying means in position to permit the card to be perforated.

59. In a machine of the class specified, the combination of punching mechanism comprising two sets of punches and a movable die, the latter comprising a pair of plates spaced apart, power driven means for shifting said die into position to coöperate with both sets of said punches, key levers effective to select and lock the individual punches of one set of punches in position, means for releasing all of said key levers simultaneously and operated by said power driven means, counting mechanism connected with certain of said key levers and preliminarily controlled by said key levers, means operated by the power driven means for actuating said counting mechanism, a single operating key for throwing said power driven means into operation, card carrying means secured to said die and shiftable therewith and also shiftable intermediate the plates of said die, means for automatically locking said card carrying means in position to permit the card to be perforated, and means for releasing said locking means.

60. In a machine of the class specified, the combination of punching mechanism comprising two sets of punches and a movable die, the latter comprising a pair of plates spaced apart, power driven means for shifting said die into position to coöperate with both sets of said punches, key levers effective to select and lock the individual punches of one set of punches in position, means for releasing all of said key levers simultaneously and operated by said power driven means, counting mechanism connected with certain of said key levers and preliminarily controlled by said key levers, means operated by the power driven means for actuating said counting mechanism, a single operating key for throwing said power driven means into operation, card carrying means secured to said die and shiftable therewith and also shiftable intermediate the plates of said die, means for automatically locking said card

carrying means in position to permit the card to be perforated, means for releasing said locking means, and means for shifting the card carrying means from between said 5 plates.

61. In a card punching machine, the combination of census-card punching mechanism comprising a series of punches, key operated levers for selecting and setting the 10 punches in their punching positions, and power driven means for automatically carrying the card to be punched into position to permit all of the punches to perforate the card at the same time.

62. In a card punching machine, the combination of census-card punching mechanism comprising a series of punches, key operated levers for selecting and setting the 15 punches in their punching positions, power driven means for automatically carrying the card to be punched into position to permit all of the punches to perforate the card at the same time, and a single actuating key for controlling the operation of the power 20 driven means subsequent to the setting of the punches.

63. In a card punching machine, the combination of a series of key actuated census-card punches settable independently of each 30 other or a plurality thereof together, and power driven means for automatically carrying the card to be punched into position whereby all of the set punches will perforate the card at the same time.

64. In a card punching machine, the combination of a series of key actuated census-card punches settable independently of each 35 other or a plurality thereof together, power driven means for automatically carrying the card to be punched into position whereby all of the set punches will perforate the card at the same time, and a key operated lever for controlling said power driven means.

65. In a card punching machine, the combination of a series of key actuated census-card punches settable independently of each 45 other or a plurality thereof together, power driven means for automatically carrying the card to be punched into position whereby all of the set punches will perforate the card at the same time, and counting mechanism operated simultaneously with the punching of the card to indicate the total holes punched in successive cards.

66. In a machine of the class specified, the combination of punching mechanism including a series of punches, means for selecting 55

and setting the punches in their punching positions to punch a plurality of holes simultaneously in either a vertical or a horizontal row, card carrying means, and power driven means for operating the mechanism whereby all of the set punches will perforate the work at the same time. 60

67. In a machine of the class specified, the combination of punching mechanism including a series of punches, means for selecting and setting the punches in their punching positions to punch a plurality of holes simultaneously in both horizontal and vertical 70 rows, card carrying means, and power driven means for operating the punching mechanism whereby all of the set punches will perforate the work at the same time in both horizontal and vertical rows. 75

68. In a card punching machine, the combination of card punching mechanism including a plurality of rows of punches, key operated means for selecting and locking any of the punches in the several rows in 80 their punching positions thereby to punch a plurality of holes simultaneously lengthwise or crosswise of the card, or both, card carrying means, and power driven means for automatically operating the punching 85 mechanism whereby all of the set punches will be operated at the same time.

69. In a card punching machine, the combination of card punching mechanism including a shiftable die, card carrying means 90 shiftable transversely of the plane of movement of said die punches and into position above said die cooperatively with the punches thereby to be shifted with the die, and power driven means operating said die thereby to 95 punch the card carried by the card carrying means.

70. In a card punching machine, the combination of card punching mechanism comprising a series of punches, key operated selecting and locking mechanism for setting the punches, card carrying means shiftable in a plane transverse of the plane of movement of the punches thereby to carry a card into position to be punched, and power driven means for then shifting the card carrier and its card into position to engage the set punches thereby to punch the card. 100 105
